UNITED STATES PATENT OFFICE.

HARRISON L. STALEY, OF MARTINSVILLE, INDIANA, AND WALTER B. SIMMONS, OF RICHMOND, VIRGINIA, ASSIGNEES TO WILTS VENEER COMPANY, OF RICHMOND, VIRGINIA, A CORPORATION OF NORTH CAROLINA.

PAIL-BOTTOM FASTENER.

1,297,411.

Specification of Letters Patent. Patented Mar. 18, 1919.

Application filed October 7, 1916. Serial No. 124,309.

To all whom it may concern:

Be it known that we, HARRISON L. STALEY and WALTER B. SIMMONS, citizens of the United States of America, and residents, respectively, of Martinsville, county of Morgan, and State of Indiana, and Richmond, county of Henrico, and State of Virginia, have invented certain new and useful Improvements in Pail-Bottom Fasteners, of which the following is a full and clear specification.

The object of this invention is to provide the lower end of a shipping vessel with a sheet metal band that will at the same time perform the function of a hoop, a chime, and a bottom fastening, and will also greatly stiffen and strengthen the lower end of the vessel, where the greatest strength is needed to enable it to withstand the rough usage 20 these articles are subjected to in transportation.

In the drawings—

Figure 1 is a side elevation of a portion of the bottom of a candy pail or other shipping vessel constructed in accordance with our invention;

Fig. 2 a vertical section thereof;

Fig. 3 a horizontal sectional view showing the band in process of being fastened;

Fig. 4 a detail view showing the band being pressed into position; and

Fig. 5 a detail perspective view of a fragment of the combined hoop, chime, and bottom fastener.

In the drawing annexed, *a* designates the body of the pail or other vessel, and *b* the bottom thereof, which fits up against the bottom edge of the pail body. To clamp the pail body in place, we provide a sheet metal band *c* which closely fits the pail at the bottom edge thereof and is fastened securely to the exterior of the pail by any suitable means, preferably by nail-like points *d* formed integral with the band and driven into the pail body and clenched on the interior thereof, as fully disclosed and claimed in our co-pending application Serial No. 94,158, filed April 28, 1916.

The lower edge of the band is bent inwardly and upwardly to form an annular chime *e* of arch form in cross-section, the extreme edge of this chime portion pressing against the lower face of the bottom *b* and

serving to clamp the same hard up against the lower edge of the pail body. The edge 55 of the bottom fits solidly against the inner face of the band, so that the bottom is held rigidly in place without extraneous fastening devices.

It will be observed that our device serves 60 the three-fold function of a hoop for the lower end of the pail body, a fastening means for the bottom, and also as a chime-like foot flange for the pail, this flange being arch-like in cross-section to obtain the 65 maximum of strength for any given thickness of sheet metal. In this way, we provide an exceedingly simple and inexpensive way of fastening the bottom of the pail and at the same time strengthen the pail just where 70 the greatest strength is needed, and it will be observed that these advantages are obtained without exposing the contents of the pail to any metal surfaces, except the inner clenched ends of the points *d*, the parts of these points 75 that are exposed on the interior being so small as to be negligible.

It will be observed that the free edge of the arched chime *e* bears against the bottom on an annular line at a distance from the inner face of the pail wall. The result of this is that when this inner annular edge is pressed hard against the bottom all around and the bottom is made of thin material, the bottom will be slightly bulged upwardly at its center, thus slightly arching the bottom upwardly. This not only insures a very tight joint between the bottom and the lower edge of the pail body, but also insures maximum strength in the bottom and in the pail 90 structure. With the bottom thus arched upwardly, it will be observed that it will more effectively resist strains due to the weight of the contents of the pail, and it will be observed that a material part of the strain due 95 to the weight of the contents will be taken up in a sort of circumferential thrust against the free edge of the chime, thereby tending to hold the bottom tight against the bottom edge of the pail body. It will be observed 100 also that the free edge of the chime *e* is forced into the lower face of the bottom and forms a groove therein, thereby anchoring the free edge of the chime in the body of the bottom at a distance from the rim there- 105 of, whereby the bottom and the chime will

be securely interlocked and the bottom will be held rigidly against lateral displacement without the employment of extraneous fastening devices.

5. In applying the band to the pail, we simply invert the same and, after placing the bottom in place, slip the band down over the pail body and the bottom with the free edge of the chime resting on the bottom, as shown 10 in Fig. 4; then, by means of a suitable plate or plunger *f*, pressing against the arched part of the chime, the band is rammed home sufficiently hard to force the free edge of the chime to form a groove in the bottom 15 member, and then, while thus held tightly in place, the anchoring devices *d* are driven into the body of the pail.

Having thus described our invention, what we claim is:

- 20 1. The combination with a cylindrical shipping vessel having a grooved bottom fitting up against its lower edge, of a metal band fitted around the bottom of the vessel and having its upper edge anchored thereto 25 and its lower edge depending below the bottom and bent inwardly and upwardly, the upwardly-bent edge being pressed against the under surface of the bottom and forcibly into said groove, to thereby clamp the bottom against the lower edge of the pail and support the bottom entirely upon the said edge, said edge serving to hold said bottom against lateral displacement.

2. The combination with a cylindrical 30 body and a bottom fitting up against the lower edge thereof, of a combined hoop and chime and bottom fastener having an annular arched portion whose edge is anchored rigidly in the under surface of the bottom 40 at a distance from the edge.

3. The combination with a cylindrical body and a bottom fitting up against the lower edge thereof, of a combined hoop and chime and bottom fastener having an annular arched portion whose edge is anchored 45 to the under surface of the bottom at a point inside of the inner face of the body of the vessel.

4. The combination with a cylindrical body and a bottom fitting up against the bottom edge thereof, of a combined hoop and chime and bottom fastener consisting of a band embracing the lower edge of the body and the edge of the bottom and having anchoring means at its upper edge engaging 50 the cylindrical body and an arch-like chime formed at its lower edge, this chime extending inwardly and upwardly and being anchored in a groove in the under surface of 55 the bottom.

5. In a cylindrical vessel, a bottom fitting against the lower edge of said vessel, and a metal band surrounding the lower edge of the vessel and anchored thereto, the lower annular edge of this band extending beyond 60 the lower face of the bottom and being curled inwardly to an arch form in cross section, the upwardly-directed annular edge of this arch-like portion being forcibly embedded into the bottom at a point inside of the plane of 65 the wall of the vessel to thus clamp the bottom against the lower edge of the vessel and cause the bottom to arch upwardly, the bottom being supported entirely on said upwardly-bent edge.

In testimony whereof we hereunto affix our signatures this 6th day of October, 1916.

HARRISON L. STALEY.
WALTER B. SIMMONS.
